[57] CLAIM

The ornamental design for a through-type capacitor, as shown and described.

DESCRIPTION

FIG. 1 is a front-left side perspective view of a through-type capacitor according to our new design;
FIG. 2 is a rear-left side perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a bottom plan view thereof;
FIG. 8 is a top plan view thereof;
FIG. 9 is a front, left side perspective view of a second embodiment of our new design;
FIG. 10 is a rear-left side perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a bottom plan view thereof;
FIG. 16 is a top plan view thereof;
FIG. 17 is a front, left side perspective view of a third embodiment of our new design;
FIG. 18 is a rear-left side perspective view thereof;
FIG. 19 is a front elevational view thereof;
FIG. 20 is a rear elevational view thereof;
FIG. 21 is a left side elevational view thereof;
FIG. 22 is a right side elevational view thereof;
FIG. 23 is a bottom plan view thereof; and
FIG. 24 is a top plan view thereof.
